UNITED STATES PATENT OFFICE.

THEODORE HAVILAND, OF AMBAZAC, FRANCE.

DESIGN FOR A SIRUP-JUG.

SPECIFICATION forming part of Design No. 22,028, dated December 6, 1892.

Application filed October 11, 1892. Serial No. 448,585. Term of patent 14 years.

To all whom it may concern:

Be it known that I, THEODORE HAVILAND, a citizen of the United States, residing at Am-bazac, in the Department of the Haute-Vienne 5 and Republic of France, have invented and produced a new and original Design for Molasses or Sirup Jugs; and I do hereby declare the following to be a full, clear, and exact description of the same, reference being had to 10 the accompanying drawings, forming a part thereof.

Figure 1 represents a sectional view of a molasses or sirup jug. Fig. 2 is a face view of the same. These two views are deemed 15 necessary to fully illustrate my design.

The principal feature of my design consists in the elongation of the neck of the jug with perforations in the cover or at the upper part of the neck; also, of having a scroll turned 20 upward below the spout from the lower part of the jug, so as to form a cup or lip.

In sectional view Fig. 1 the length of the neck will be observed.

The dotted line A B shows the height to 25 which the liquid can rise.

Two protruding lips are represented as rising from the interior sides of the jug toward each other. C D, the more pronounced lip, is on the side of the spout.

The cover F is fitted into the neck G, and 30 the perforations H H H are made either in the cover or upper portion of the neck.

In Fig. 2, below the spout J, a scroll K is turned up from the lower part of the jug to 35 form a lip or cup.

The jug can be entirely of one material—such as china, earthenware, or glass—and it can be all of metal or partly of metal, as desired.

What I claim is—

The design for a molasses or sirup jug, substantially as shown and described.

In testimony whereof I affix my signature in presence of two witnesses.

THEODORE HAVILAND. [L. S.]
